VERNON C. FAUNCE, OF BONDSVILLE, MASSACHUSETTS.

LAP-ROD RETAINER FOR PICKERS, CARDING-ENGINES, &c.

1,216,790.

Specification of Letters Patent. Patented Feb. 20, 1917.

Application filed April 6, 1916. Serial No. 89,255.

To all whom it may concern:

Be it known that I, VERNON C. FAUNCE, a citizen of the United States, residing at Bondsville, in the county of Hampden, State 5 of Massachusetts, have invented a certain new and useful Improvement in Lap-Rod Retainers for Pickers, Carding-Engines, &c., of which the following is a specification, reference being had therein to the accompanying 10 drawings.

The invention provides novel means for preventing a lap-rod used in connection with a wound roll of feed-lap from working endwise so as to become free at one end thereof 15 from the bearing or guide for such end. The invention is applicable to intermediate and finisher-pickers, to carding machines, and to other machines in which fibrous material in lap-form wound in rolls is operated upon. 20 When a lap-rod works endwise and becomes disengaged at one end thereof from the bearing or guide for such end, the onward traveling movement of the feeding conveyer-apron causes the roll of lap and lap-rod to 25 swing into a more or less forwardly-inclined position. In the case of a wound roll of full or substantially full diameter which has been thus swung, the swinging thereof will carry an end-portion of the wound mass 30 forward against the feed-roll arrangement, or against the lap-roll next in advance, as the case may be. If the one that is swung is the one next the feed-roll devices, portions of several layers of the lap will be 35 drawn in in a mass, with the result of blocking the feed, sometimes with breakage of gearing. If the lap-roll in question is the second or succeeding roll, its forwardly swung end will make contact with the next 40 one in advance, and both will be prevented from turning, thereby blocking the feed on the apron. In the case of a nearly exhausted lap-roll, the final portion of the wound lap may slide bodily from the displaced lap-rod without unwinding, and in a 45 mass pass through the feed-roll arrangement. The disengaged end of the lap-rod itself, in the case of the lap-rod of the first or leading lap-roll, may be swung around and go through the feed-roll arrangement into the interior of the machine, so that injury to the machine will follow from engagement of

the beater or revolving toothed-cylinder next adjoining said feed-roll arrangement with the lap-rod. 55

The drawings show an embodiment of the invention.

Figure 1 of the drawings shows certain portions of an intermediate or finisher-picker, mainly in vertical section, including 60 lap-feeding devices having the said embodiment of the invention applied thereto.

Fig. 2 is a view showing in elevation on a somewhat larger scale than Fig. 1 one of the lap-rolls of Fig. 1 and its lap-rod, with 65 the means for preventing endwise movement of the lap-rod.

Fig. 3 is a plan view of the parts that are shown in Fig. 2.

Having reference to the drawings,— 70
Fig. 1 shows two wound rolls 1 and 2 of lap resting by the peripheries thereof upon the upper run of the feeding conveyer-apron 3 by which the unwound lap resting upon the said upper run is delivered to the 75 feed-roll arrangement, the latter comprising in the present instance a feed-roll 4 and a series of evener-plates 5, the lap being fed by means of the rotation of the said roll between the roll itself and the evener-plates 80 to the beater 6 rotating within the casing 7 and adjacent the grid 8. At 9, 9, are represented lap-rods, occupying as usual central longitudinal openings through the respective lap-rolls and projecting at opposite ends 85 of the lap-rolls so as to engage with the up-standing guides or bearings 10, 10, upon the cheeks or side-pieces 11, 11, which are employed in practice at the opposite edges of the feeding conveyer-apron 3. Usually the 90 end portions of the lap-rods project outwardly past the cheeks or side-pieces 11, 11, as shown best in Fig. 3, at both sides of the machine.

In carrying the invention into effect I 95 apply to a cheek or side-piece 11 adjacent each guide or bearing 10 an outstanding bracket 12 having a rod-engaging portion 12^a rising alongside the guide or bearing at a distance from the latter corresponding with 100 the length of rod which is to be permitted to extend outward beyond the guide or bearing. This retaining device, constructed substantially as shown in the drawings, may

be duplicated in connection with the guides or bearings for the opposite end-portions of a lap-rod, but by forming or providing the lap-rod at one end thereof with a radially-projecting disk-like head or collar 9^a as in the drawings, adapted to engage with the outer side-portion of the corresponding guide or bearing 10, it will be sufficient to employ a retainer-device 12^a at one end only of a lap-rod. In such case, the retainer-device will prevent longitudinal displacement of the lap-rod outwardly in one direction and the collar or head, through its engagement with the guide or bearing, will serve to limit longitudinal displacement of the lap-rod in the other direction.

The upright portion 12^a of the retainer preferably is provided with an outwardly flaring wing or flange 12^b, shown best in Fig. 3, which serves to guide the adjacent end of a lap-rod into place at the inner side of the retainer 12^a when the lap-roll with the lap-rod applied thereto is advanced into position by movement in the direction of travel of the upper run of the conveyer-apron 3 from a preliminary position between two sets of guides or bearings 10, 10. Thereby the work of placing a fresh roll of lap in position in connection with the guides or bearings for its lap-rod is facilitated.

The form, construction, and mode of application of retainer-devices according to my invention may be varied in practice. Such retainer-devices may be provided for use in connection with all of the supply lap-rolls at the feeding end of a picker or other machine, or may be applied in connection with only the lap-roll or lap-rolls next adjacent the feed-roll arrangement.

What is claimed as the invention is:

1. The combination with a support upon which the periphery of a wound lap rests, and a guide for one end of a lap-rod located adjacent the position of one end of the lap-roll, restraining the lap-roll from forward displacement and permitting vertical movement of the lap-rod as the diameter of the wound lap varies, of a lap-rod retainer outside said guide, adjacent thereto, and in line 45 with the corresponding end of the lap-rod, whereby endwise movement of the lap-rod outward is limited without interference with said vertical movement of the lap-rod.

2. The combination with a lap-rod support at the feeding end of a picker or other machine to which fibrous material is fed in lap-form, said feeding end having at one side thereof a guide for one end of a lap-rod extended through a supply roll of lap, 55 said guide adapted to restrain the lap-roll from forward displacement but permitting vertical movement of the lap-rod as the diameter of the wound lap varies, of a lap-rod retainer outside said guide, in line with the corresponding end of the lap-rod, where-

by endwise movement of the lap-rod in the direction of such retainer is limited without interference with said vertical movement of the lap-rod.

3. The combination with a lap-roll support and a guide for one end of a lap-rod, located adjacent the position of one end of a wound lap-roll, said guide adapted to restrain the lap-roll from forward displacement but permitting vertical movement of the lap-rod as the diameter of the wound lap varies, of a lap-rod retainer outside said guide, adjacent thereto, and in line with the corresponding end of a lap-rod engaging said guide, whereby endwise movement of the lap-rod outward is limited without interference with said vertical movement of the lap-rod, and a lap-rod having a head or collar adapted to engage said guide to limit thereby endwise movement of the lap-rod in the opposite direction.

4. The combination with a lap-roll support at the feeding end of a picker or other machine to which fibrous material is fed in lap-form, and a guide for one end of a lap-rod extended through a supply roll of lap, said guide adapted to restrain the lap-roll from forward displacement but permitting vertical movement of the lap-rod as the diameter of the wound lap varies, of a lap-rod retainer outside said guide, in line with the corresponding end of the lap-rod, whereby endwise movement of the lap-rod in the direction of such retainer is limited, and a lap-rod having a head or collar adapted to engage said guide to limit thereby endwise movement of the lap-rod in the opposite direction.

5. The combination with a guide or bearing for one end of a lap-rod, said guide or bearing located adjacent the position of one end of a wound lap-roll, of a lap-rod retainer outside said guide or bearing, adjacent thereto, and in line with the corresponding end of a lap-rod engaging said guide or bearing, whereby endwise movement of the lap-rod outward is limited, and a guide whereby as a lap-roll is advanced horizontally into working position the said end of the lap-rod is directed into position at one side of the retainer.

6. The combination with a guide or bearing for one end of a lap-rod, of a lap-rod retainer outside said guide or bearing, adjacent thereto, and adapted to engage with the outstanding portion of the lap-rod to limit endwise movement of the latter, and a guide by which the said portion of the lap-rod is directed into working relations with the retainer as a lap containing the lap-rod is placed in working position.

7. The combination with the feeding end of a picker or other machine to which fibrous material is fed in lap-form, said feeding end having at one side thereof a guide or bear-

ing for one end of a lap-rod extended through a supply roll of lap, of a lap-rod retainer outside said guide or bearing, in line with the corresponding end of the lap-rod, whereby endwise movement of the lap-rod in the direction of such retainer is limited, and a guide by which the end of the lap-rod is directed into working relations

with the retainer as a lap containing the lap-rod is placed in working position. 10

In testimony whereof I affix my signature in presence of two witnesses.
